UNITED STATES PATENT OFFICE.

WEBB JAY, OF CHICAGO, ILLINOIS.

VALVE MECHANISM FOR VACUUM FEED DEVICES.

1,293,789.

Specification of Letters Patent. Patented Feb. 11, 1919.

Application filed April 8, 1918. Serial No. 227,362.

To all whom it may concern:

Be it known that I, WEBB JAY, a citizen of the United States, residing at Chicago, in the county of Cook and the State of Illinois, have invented certain new and useful improvements in Valve Mechanism for Vacuum Feed Devices, of which the following is a specification, reference being had to the accompanying drawings, forming a part thereof.

The purpose of this invention is to provide a simple and economical valve mechanism in the form of a unitary fitting, to be used in the well understood type of liquid feeding apparatus employing alternation of suction and atmospheric pressure for lifting the liquid from a lower to a higher level. The invention consists in the features and elements of construction hereinafter described and shown in the drawings as indicated by the claims.

In the drawings:

Figure 1 is a diagrammatic view of a liquid feeding system of the type to which this invention is applicable.

Fig. 2 is a vertical section of the so-called vacuum tank which is the upper receptacle for liquid embodying a chamber in which the alternation of suction and atmospheric pressure is effected, and another chamber in which the elevated liquid is stored for use. This view shows in section the fitting including the valve mechanism embodying this invention.

Fig. 3 is a sectional detail of a valve mechanism of a slightly modified form which may be substituted for that shown in Fig. 2.

Referring first to Fig. 2 of the drawings, the tank, or chamber, 1, will be recognized as the usual outer chamber of an apparatus of this type having suspended within it a slightly smaller chamber, 2, inclosing a float, 3, supported on one arm, 4, of the bell crank, whose other arm, 5, is connected by a spring, 6, to a lever, 7, fulcrumed on the pivot of the bell crank, and extending up through an opening, 8, in the cover of the chamber, 2. Over the opening, 8, is mounted a fitting, 9, which is provided with two openings, one leading to a screen, 10, through which atmosphere may be admitted and the other leading to a pipe, 11, which as indicated in Fig. 1, is connected to a source of suction such as the intake manifold of an internal combustion engine. These two openings of the fit-

ting, 9, are controlled respectively by valves, 12 and 13, carried at opposite ends of a common pin or rod, 14, whose end portions are shown as threaded for receiving said valve members, while enlarged portions, 15 and 16, of said valve stem or rod, 14, serve both as stops to limit the position of valves, 12 and 13, when they are applied to the threaded ends of the stem, and also provide abutments on said stem to engage the upper end of the lever, 7, which may be apertured or forked for the purpose.

It may be understood that liquid entering the chamber, 2, through the supply pipe, 17, which may lead from any convenient source of supply at a position lower than that of the chamber, 2, will be drawn into said chamber, 2, by virtue of the reduced pressure therein, so long as an adequate degree of suction is maintained in the pipe, 11, and valve, 13, remains open; but, as the quantity of liquid in chamber, 2, increases and carries the float, 3, upward with it within the chamber the resulting angular movement of the bell crank to whose arm, 4, the float is attached will carry the spring, 6, past the fulcrum of said bell crank, causing it to pull upon the lever, 7, from the opposite side, and to swing said lever along the middle reduced portion of the valve rod, 14, against the abutment formed by the enlarged portion, 15, thus moving the valve rod, 14, in direction to close the valve, 13, and open valve, 12, for admitting atmospheric pressure to the chamber, 2. The partial vacuum in the chamber being thus dissipated, the check valve, 18, at the bottom of chamber, 2, heretofore held closed by the reduced pressure in the chamber, will automatically open permitting the liquid contents to discharge by gravity into the outer chamber or receptacle, 1, and, thence to flow by gravity through the pipe, 19, to carburetor, 20, of an internal combustion engine, 21, seen in the diagram of Fig. 1. Such gravity flow from the chamber, 1, is rendered possible at all times by the provision of an air vent, 22, in said chamber, and it will be understood, of course, that the main supply tank, 23, from which pipe, 17, leads, is also subject to atmospheric pressure.

As shown in Fig. 2 the fitting, 9, is formed with a foot flange, 24, which may be secured against a boss in the cover of chamber, 2, by means of screws, 25, with

packing material interposed at 26. The screen, 10, is held in position by a threaded cap, 27, and a corresponding cap, 28, is screwed onto the other end of the fitting and arranged to receive the coupling from the pipe, 11. The valves, 12 and 13, are slidably supported in the small chambers provided for them respectively at opposite sides of the openings which they control, the walls of such chambers being formed with guide ribs, 29.

In the form of fitting shown in Fig. 2, the opening of the atmospheric valve, 12, is necessarily accomplished in opposition to the suction tending to hold such valve on its seat. In cases where it is preferred to have the opening of the suction valve subject to this resistance rather than the opening of the air valve, the valve arrangement may be reversed as shown in Fig. 3, providing for valves, 12^x and 13^x, respectively seating on the inner sides of their ports instead of on the outer sides as in Fig. 2. In this fitting, 9^x, a slightly modified form of lever, 7^x, operates the valve substantially as in the other form and the remaining parts are quite similar to those in Fig. 2, except that the valve members are provided with guides, 30, projecting from the members themselves, and riding upon the smooth cylindrical walls of the chambers between the ports and the passages controlled thereby. These guides, 30, are merely radial ribs preferably three in number on each valve, projecting into contact with the cylindrical wall, upon which they travel a short distance in the seating and unseating movement.

I claim:

1. In a liquid feeding apparatus including a supply tank, an auxiliary chamber and a source of suction, a valve fitting for said chamber comprising a pair of opposed ports opening to a common passage which com-

municates with the chamber, a pair of valves for said ports respectively, and a common valve stem on which they are mounted and spaced apart by distance different from that between the two valve seats, means guiding said stem for oscillation for alternate seating of said valves, one valve controlling a connection with the source of suction, and the other controlling an atmospheric vent, and means controlled by the liquid in said chamber effecting such oscillation.

2. In the combination set forth in claim 1, said liquid-controlled means comprising a float in said chamber and a lever connected thereto and engaging between said valves for effecting such oscillation of their stem.

3. In the combination set forth in claim 1, said liquid-controlled means including a lever fulcrumed in the chamber, a float connected to one arm of the lever, a second lever on the same fulcrum connected to the other arm of the first by a spring and extending to engage between said valves for controlling them.

4. In the combination set out in claim 1, said valve stem having shoulders spaced apart between said valves, and the means controlled by the liquid in the chamber including a lever mounted to play between said shoulders and to move farther than the distance between them for alternately seating said valves.

5. In the combination set out in claims 1 and 4, a second lever on the same fulcrum as the first, a float connected to one arm of said lever within the chamber and a spring connecting the other arm with the first lever for control of its movement by travel of the float in the chamber.

In testimony whereof, I have hereunto set my hand at Chicago, Illinois, this 3rd day of April, 1918.

WEBB JAY.
